UNITED STATES PATENT OFFICE.

TOMLINSON FORT JOHNSON, JR., OF ATLANTA, GEORGIA.

CIRCUIT-OPENING DEVICE.

Application filed August 16, 1919. Serial No. 318,026.

To all whom it may concern:

Be it known that I, TOMLINSON F. JOHNSON, Jr., a citizen of the United States, residing at Atlanta, in the county of Fulton and State of Georgia, have invented a new and useful Circuit-Opening Device, of which the following is a specification.

This invention has reference to automatic circuit opening devices, known in the trade 10 as automatic skeet switches, and its object is to permit a very marked diminution in the cost of building transformer stations, whereby it is possible to serve a customer at a very much lower first cost than has heretofore been done, and so it is feasible to take on many customers which could not be done with former types of station installations because the income from the necessary investment was insufficient to pay a sufficient 20 return upon such investment.

In accordance with the invention high tension line wires, say, carrying from 11,000 volts to 22,000 volts or more, are each connected up to a switch structure through which 25 the current is fed to the high tension side of a transformer to be afterward delivered by the low tension side thereof. The arrangement is such that in the event of a dangerous rise of current from any cause the continuity of the line wire is broken through 30 the cut-out of any one or more of the lines and the circuit may be restored by purposely breaking the circuit of the other lines of the group, considering a three phase system, to be afterward restored in all the 35 branches of the three phase system.

The invention will be best understood from a consideration of the following detailed description taken in connection with 40 the accompanying drawings forming part of this specification, with the understanding, however, that the invention is not confined to any strict conformity with the showing of the drawings, but may be changed and modified so long as such 45 changes and modifications mark no material departure from the salient features of the invention as expressed in the appended claims.

50 In the drawings:—

Figure 1 is an elevation, partly in section, of a circuit breaker or skeet switch embodying the invention.

Figure 2 is an elevation, partly in section, 55 of a portion of the circuit breaker, with the parts in open circuit position.

Figure 3 is a plan view of the yoke member of the circuit breaker shown in Figure 2.

Figure 4 is a more or less diagrammatic 60 view of a portion of the system including the circuit breaker.

Figure 5 is a perspective view of a lever forming part of the circuit breaker.

Referring to the drawings, there is shown 65 a pole 1 which may, for example, be of standard two inch iron pipe, although not confined to any such particular size. Surmounting the pipe 1 is a cap 2 carrying a pedestal 3 in turn carrying a pin 4 of suitable material, say of locust. The pin carries a pin-type insulator 5 surmounted by a cap 6 conveniently made of cast iron and held to the insulator by screws 7. The cap 6 is provided at suitable points with bosses 70 8 each having a perforation 9 entered crosswise by a set screw 10 permitting the attachment to the cap of conductors 11 and 12 Fig. 4 to which reference will hereinafter be made. Fast to the cap 6 on top of the 80 latter is an inverted bell 11^a rising from the interior of which is an insulator 12^a preferably, though not necessarily, of the type known as a delta star insulator. Carried by the insulator 12^a is another bell 13 having 85 its edges separated from the first bell by a suitable distance. Each bell is provided with a lug 14 entered by a screw 15, the two screws serving to carry a fuse strip 16 electrically connecting the two bells. On the 90 bell 13 there is mounted a stirrup 17 connected through the bell 13 to the insulator 12^a by a suitable screw or bolt 18. One leg of the stirrup 17 terminates at its upper end in a guide 19 and the other leg similarly terminates in a guide 20 in line with the guide 19. Alined with and capable of passing through both guides 19 and 20 is a rod 21 having a threaded portion 22 at one end and a circumferential groove 23 close to the 95 other end. Extending lengthwise of the rod 21 along one side thereof is an elongated groove 24. The guide 19 has a central bore 100 for the rod 21 and slots 26, 27, entering the bore on opposite sides of a division partition 28. Lodged in the groove 24 is a stop pin 29 having ends 30 and 31 respectively, bent into the slots 26 and 27 so as to partially embrace the partition 28 in a manner 105 to permit longitudinal movement of the rod 21 for a distance equal to the greater portion of the length of the rod and yet anchor

the rod against escape from the stirrup. Surrounding the rod 21 is a helical spring 32 and applied to the threaded end 22 of the rod is a wing nut 33. The action of the 5 spring 32 at one end against the guide 19 and at the other end against the wing nut 22 is to move the rod to bring the groove 23 and the corresponding end of the rod 21 within the guide 19. The wing nut 33 provides means whereby more or less compression 10 may be put upon the spring 32 at the will of an operator.

The guide 20 is provided with a passage 34 for the end of the rod 21 having the 15 groove 23 and continued in the guide 20 is a side extension 35 of the bore 34. At one side of the guide 20 are ears 36 between which is pivoted a lever 37 having an elongated arm 38 at one side of the pivot and 20 a short arm 39 at the other side thereof, the extremity of the arm 39 being provided with a notch 40 to engage the groove 23 when the corresponding end of the rod 21 is in the bore 34 and the groove 23 projects 25 beyond the outer end of the bore 34. In such case, that is, with the arm 39 engaging the rod 21 at the groove 23, the arm 38 of the lever is horizontal or approximately so.

At an appropriate point of the arm 38 30 there is provided a perforation 41 to which one end of a wire 42 is attached. The other end of this wire is passed through the perforation 43 in the free end of an arm 44, projecting from the arm of the stirrup 17 35 carrying the guide 20. When the parts are set, that is with the rod 21 projecting through the bore 34 of the guide 20 and the spring 32 compressed, with the rod 21 locked by the lever 37 held in place by the 40 wire 42, the latter is closely adjacent to the fuse 16. If, now, a current sufficiently strong to melt the fuse 16 should pass through it, the fuse is blown and ordinarily this will cause the breakage of the wire 42. 45 If not, an arc is formed to the wire 42 quickly rupturing it. This releases the lever 37 to the action of the spring 32, the lever readily turning on the pivot carried by the ears 36 and the rod 21 is pulled away 50 from the lock formed by the arm 39 of the lever 37 until that end of the groove 24 close to the groove 23 is reached and further movement of the rod 21 is arrested by the stop end 31.

55 When the rod 21 is in the locked position it traverses a clamp structure 45 like that shown in Letters Patent #1,244,339, granted to me October 23, 1917, for a snap clamp or grip for electric conductors, and hence needing no particular description. The clamp 45 is of a character which permits it to be readily applied to or removed from the rod 21 after the latter has been locked in place, or in the event of the wire 42 being broken 60 the spring 32 is strong enough to pull the

rod 21 from traversing relation to the clamp 45.

The circuit breaker or skeet switch is arranged near an incoming line wire 48, shown 70 in Figure 4. Attached to this wire by a suitable clamp 49 is another wire or conductor 50 of flexible character carried through a guide 51 fast to the line wire 48 or merely to a guy continuation 52 thereof for sustaining the adjacent end of the incoming line wire. The wire 50 is continued through the guide 51 and is capable of moving therethrough and then drops and is secured to the clamp 45. The wire 50 is designed to serve as a live or charged continuation of the line wire 48 and when the installation is complete current may flow from the line wire 48 through the continuation 50 to the clamp 45 to which the line wire continuation 50 is made fast. Under 80 these circumstances current flows from the line wire 48 through the continuation 50, clamp 45, rod 21, stirrup 17, to the bell 13, thence by way of the fuse 16 to the bell 11^a, and ultimately to the cap 6 from which latter the current is carried by the conductor 11 to a suitable transformer 53 where the voltage is reduced and the current at reduced voltage leaves by way of a conductor 54 to a suitable point of utilization. The 85 conductor 11 may be continued by way of a jumper 55 to another main line around the transformer 53. The conductor 12 connects the cap 6 with a lightning arrester 56 of suitable type. 90

Between the junction of the conductor 50 with the incoming line 48 and the guide 51 there is provided a weight 57 carried by a roller 58 resting on the conductor 50 so that the latter is always under tension sufficient 105 to raise the clamp 45 out of possible engagement with the yoke 17 when the rod 21 is released and withdrawn from the clamp 45. 100

So far as this invention is concerned it is only deemed necessary to show one unit, 110 for a three-phase installation is but a repetition of the one unit illustrated. In case of the blowing of a fuse and the rupturing of the continuity of the corresponding line wire, the other line wires, in a three phase 115 station, then have their continuity broken by purposely moving the respective levers 37 to release the corresponding rods 21. This causes the raising of the clamps 45 to the desired height, which height may be 120 determined by the presence of a stop 59 fast on the wire 50 in position to engage the guide 51 when the clamp 45 has been raised to a determined height. 125

The flexible feeding conductor 50, together with guide 51, weight 57 and clamp structure 45, are shown generally, but in more or less modified relations, in other applications filed by me on May 13, 1920, Serial No. 381,134, for skeet head, and 130

Serial No. 381,135, filed May 13, 1920, for "throw-off" or circuit breaking switch for skeet heads". The claims in this case are intended to be sufficiently comprehensive to cover such devices in the broader sense.

What is claimed is:—

1. A circuit opening device, comprising a member for attachment to a line wire, holding means for said member having a normal tendency to release it, a latch for retaining the holding means against its normal tendency, and means for holding the latch, actuated by an abnormal rise of current to release the latch.
2. A circuit opening device for high tension transmission lines, comprising a clamp member connected to the line, holding means for the clamp member having a normal tendency to release the clamp member, latch means for the holding means, and retaining means for the latch means actuated by the passage of abnormal current to cause the release of the clamp member and the rupture of the continuity of the line.
3. A circuit opening device for high tension transmission lines, comprising a clamp member connected to the line, holding means for the clamp member having a normal tendency to release the clamp member, latch means for the holding means, retaining means for the latch means, and means responsive to the passage of abnormal current to cause the release of the clamp member and the rupture of the continuity of the line, said clamp member being provided with gravity means for moving it out of the way when released.
4. A circuit opening device for high tension transmission lines, comprising a clamp for attachment to the transmission line, holding means for the clamp having a normal tendency to move out of holding relation thereto, a latch for retaining the holding means in the holding position, and fusible means in the path of the line current for causing the release of the latch and holding means for the clamp.
5. A circuit opening device for high tension transmission lines, comprising a clamp for connection to the transmission line and constituting a terminal therefor, a retractile member having means for imparting to it a normal retracting tendency and movable against its normal tendency to traverse and hold the clamp, a latch for holding the retractile member against its normal tendency and thereby secure the clamp, retaining means for the latch, and fusible means in operative relation to the retaining means and positioned to pass the line current, whereby on an abnormal rise of the line current the fusible means will cause the rupture of the latch retaining means and the release of the clamp.
6. A circuit opening device for high tension transmission lines, comprising a terminal member for attachment to the transmission line, a reciprocable rod with a spring imparting a normal tendency to the rod to move it in one direction, a support for the rod in which it is movable to traverse and hold the terminal member, a latch for the rod to retain it in holding position, separated insulated conducting members carrying the support for the rod with one of the members having means for attaching a continuation of the line wire thereto, said members being arranged to be bridged by fusible means, and retaining means for the latch having means for securing it in place adjacent to the fusible means, whereby on the blowing of the fusible means the retaining means for the latch is ruptured and the latch is released.
7. A circuit opening device for high tension transmission lines, comprising a terminal member for connection with the transmission line, a slidable rod movable through the member to hold it and provided with a spring for retracting the rod to release the member, a support for the rod on which it is movable, a latch on the support for holding the rod against the action of the spring with the rod in traversing relation to the member, insulated facing bells with their adjacent edges in spaced relation, means for connecting the bells by fusible material, and a readily rupturable retaining means for the latch located in close relation to the fusible means.
8. In a circuit opening device for high tension transmission lines, the combination with a line conductor, of a flexible conductor connected at one end to the line conductor, guiding and supporting means for the flexible conductor spaced from that end of the flexible conductor connected to the line conductor, means at the other end of the line conductor for connecting the flexible conductor to the device or devices to be fed from the line conductor, and means engaging the flexible conductor between the guiding means and the connection of the flexible conductor with the line conductor for imparting to the flexible conductor a constant tendency to move the connecting means carried by the flexible conductor away from the device or devices fed by the flexible conductor.
9. In a circuit opening device for high tension transmission lines, the combination with a line conductor, of a flexible conductor connected at one end to the line conductor and at the other end provided with means for connecting the flexible conductor to a device or devices to be fed from the line conductor, and constraining means through which the flexible conductor is freely movable, for imparting to the flexible conductor a normal tendency to move away from the

- device or devices fed by the flexible conductor to separate said flexible conductor from the device or devices fed thereby beyond arcing or other dangerous distance.
- 5 10. In a circuit opening device for high tension transmission lines, the combination with a line conductor, of a flexible conductor connected at one end to the line conductor, guiding means for the flexible conductor located at an intermediate point in the length thereof to produce a loop in the flexible conductor, means for connecting the flexible conductor to a device or devices to be fed by said flexible conductor, and constraining means for the flexible conductor engaging the latter between the guiding means and the connection of the flexible to the line conductor for imparting to the flexible conductor a normal tendency to withdraw from the device or devices fed by the flexible conductor with the distance of withdrawal out of arcing or dangerous proximity thereto.
- 10 11. In a circuit opening device for high tension transmission lines, the combination with a line conductor, of a flexible conductor connected at one end to the line conductor, guiding means for the flexible conductor carried by the line conductor and producing a loop in the flexible conductor between the guiding means and the connection of the flexible conductor with the line con-
- 35 40 45 50 55
- ductor, a clamp device carried by the end of the flexible conductor remote from the line conductor for connecting the flexible conductor to a device or devices to be fed from the line conductor, and means engaging the flexible conductor at the loop therein to impart to the flexible conductor a constant tendency to move out of dangerous or harmful proximity to said device or devices.
12. An electric circuit breaker for overhead transmission lines, comprising a contact member adapted to be pendently carried from and electrically connected to the overhead conductor, with the supporting means for said contact member extensible beyond its normal position, a second contact member adapted to engage with the first-mentioned contact member when the latter is in extended position, and means for releasing the engagement between the contact members, said means being responsive to the passage of an abnormal current, whereby the circuit is opened by the return of the first contact member to its normal position.
- In testimony that I claim the foregoing as my own, I have hereto affixed my signature.
